UNITED STATES PATENT OFFICE.

GUSTAV W. HAUSER, OF JACKSON, TENNESSEE.

AWNING-ARM.

1,312,846.

Specification of Letters Patent. Patented Aug. 12, 1919.

Application filed January 10, 1919. Serial No. 270,525.

To all whom it may concern:

Be it known that I, GUSTAV W. HAUSER, a citizen of the United States, residing at Jackson, Madison county, and State of Tennessee, have invented and discovered certain new and useful Improvements in Awning-Arms, of which the following is a specification.

My said invention relates to certain improvements in the details of construction and arrangement of parts of arms for supporting awnings, particularly arms of the folding type by which the awning frame is folded against the side of the building while the awning is rolled upon the roller under the housing, and it consists particularly in features of construction whereby the central joint, or pivot, is normally held slightly to one side of, or out of line with, a line drawn from the end of the arm to the pivot in the bracket on the building, whereby the parts normally break and fold as soon as the operation of rolling up the awning is started, all as will be hereinafter more fully described and claimed.

Referring to the accompanying drawing, which is made a part hereof, and on which similar reference characters indicate similar parts,

Figure 1 is a side elevation of the awning arm as it appears attached to the side of the building and in extended position,

Fig. 2 a top or plan view of the same, and

Figs. 3, 4, 5, 6 and 7 detail views illustrating parts of the device more clearly.

In said drawings the portions marked A represent the wall or frame work around the windows of the building to which the awning is attached; B the roller on which the awning is mounted, and C the awning proper. All of said parts above referred to are, or may be, of any appropriate type and of a construction in common use. The means for operating the roller B for rolling up the awning C is not shown, such means being common and well understood.

The awning arm is composed of two parts 10 and 11 connected by a hinge, or pivot bolt 12. The upper end of arm 10 is provided with a connecting member 25 of cast metal having a hinge-part 26 connected thereto by a horizontal pivot bolt 27. Said hinge-part 26 is connected to a member 28 by a vertical pivot 15, and said member 28 is secured to bracket 13, by a horizontal bolt 14 and serrated engaging faces between

bracket 13 and member 28, as most clearly shown in Fig. 3. Said member 28 has a curved track 29 on which the upper end of member 25 is adapted to rest and travel. Said member 25 has a ball or roller 30 to take the load and reduce the friction between said parts.

Said part 10 of the arm is preferably composed of two bars bolted at one end to member 25 and at the other end to member 18, as best shown in Fig. 1, for the purpose of affording the necessary strength and rigidity, while the lower part 11 is a single member bolted to casting 21 at its upper end, and has a swiveled socket 16 on its outer end to which is attached the cross-bars 17 for supporting the lower end of the awning.

The central hinge between the parts 10 and 11 is formed of the casting 18 of a form more clearly shown in Fig. 4, and rigidly secured to the members of the part 10 of the arm, and having a semi-circular track 19 formed on the outside thereof on which a ball or roller 20, mounted in a socket in the under face of casting 21 at the upper end of part 11, is adapted to roll and thus obviate friction during the folding and unfolding movement between these parts. The top surface of the track 19 is formed inclined from both ends to a point *x*, as shown in Fig. 4, at which point the ball 20 normally finds its rest, and said point is so located as to slightly break the joint formed by the hinge 12 out of a direct line between the point of the arm and the hinge at the upper end thereof.

The swiveled socket 16 at the end of the arm also prevents any binding or strain at this point during the movement. The track 29 at the upper end on which the arm 10 moves and is supported, is also formed with a depression in its face, as at point *y* in Fig. 3, which cooperates with the depression in track 19 to hold the parts slightly out of line. By this construction an awning arm is provided which will serve to hold the awning securely in an extended position, yet is always normally ready to fold without manual attention or breaking of the joints, as soon as the operation of rolling the awning upon the roller B, is started.

In lowering the awning the arm will straighten out into position as shown in Fig. 1, the part 11 vibrating on its pivot 12 and track 19 until it finally comes to rest with the ball 20 in the lower part *x* of the

track 19 where it is maintained by gravity and in position for automatically breaking the arm when the closing operation is again started.

5 By this construction and arrangement it will be seen that when in rolled up position of the awning the parts 10 and 11 of the arms are folded together and the upper end of part 10 is swung around to the highest point on the track 29, which supports said arms in a substantially horizontal position against the side of the building. When the awning is lowered, the roller 30 rolls down into the depression *y* in the track 15 29 which brings said arms to an inclined position, as shown in Fig. 1, and the part 11 swings down on pivot 12 into extended position, as shown in Fig. 1, the ball 20 resting in the depression *x* in track 19 and thus 20 holding the two parts of the arm slightly broken around the pivot 12, as shown in Fig. 2. It will be understood that by adjusting the part 28 on the bracket 13 a greater or less angular position of the arms, 25 when extended, can be secured. It will also be understood that there is one arm at each end of the awning, and that they are mounted to break around pivot 12 in corresponding directions and manner.

30 The parts, when lowered and extended, automatically find their normal positions by reason of the freedom of movement allowed between said parts, and the normal position being determined by the lower-most points 35 *x* and *y* in the track 19 and 29 respectively.

Having thus fully described my said invention, what I claim as new and desire to secure by Letters Patent is:

1. An awning arm composed of two parts 40 hinged together, one part being provided with a track in the arc of a circle upon which a bearing on the other part is adapted to rest and travel, said track being formed

with a depression in its surface in which said bearing normally rests to hold said parts slightly deflected from a straight line between the two ends of the arm, whereby said parts are held in position to break and fold immediately upon starting the operation of rolling up the awning substantially as set forth.

2. An awning arm formed of parts hinged and adapted to fold together, one part carrying a track adjacent to the joint and the other part bearing a member adapted to 55 travel upon said track, said track being formed with a lower-most point where the bearing part normally rests and in a position to normally maintain the two parts of the arm slightly out of line with each other, 60 substantially as set forth.

3. An awning arm structure comprising a bracket for supporting said arm in position for use and carrying a curved track, a member of said arm connected to said bracket by a vertical pivot and carrying a bearing adapted to rest and travel on said track, a second member hinged to said first member of said arm, one member being provided with a track at said hinge-point and the other with a bearing adapted to rest and travel upon said track, both of said tracks being formed with depressions in their bearing faces in which the bearing parts of the respective members of the arm are adapted to normally rest and hold said parts slightly out of line with each other, 70 substantially as set forth.

In witness whereof I have hereunto set my hand and seal at Jackson, Tennessee, this 75 7th day of January, A. D. nineteen hundred and nineteen.

GUSTAV W. HAUSER. [L.S.]

Witnesses:

W. N. KEY,
C. E. BEGFORDE.
